UNITED STATES PATENT OFFICE.

RAY O. BARDON, OF UPPER SANDUSKY, OHIO.

ANTISLIPPING ATTACHMENT FOR SHOES.

1,399,682.

Specification of Letters Patent. Patented Dec. 6, 1921.

Application filed May 28, 1921. Serial No. 473,259.

To all whom it may concern:

Be it known that I, RAY O. BARDON, a citizen of the United States, residing at Upper Sandusky, in the county of Wyandot and State of Ohio, have invented new and useful Improvements in Antislipping Attachments for Shoes, of which the following is a specification.

My present invention has reference to an anti-slipping attachment for shoes.

My object is to produce a device of this character which is adjustable so that the same may be arranged on varying sizes of shoes and which includes a body that has pivotally secured thereon a spring influenced member carrying carks, said member being normally latched out of ground contacting position, but susceptible to swinging on the body to bring the carks thereof into ground contacting position and so held by the spring means.

A further object is to produce an anti-slipping attachment for shoes which can be worn without inflicting injury to a floor surface.

A still further object is to produce an anti-slipping attachment for shoes, adjustable for arrangement on different sizes of shoes, in which the carks may be sustained out of ground contacting engagement and which is cushioned so that the wearer will not be subjected to pounding shocks when the carks are in surface contacting engagement.

The foregoing, and other objects which will appear as the nature of the invention is better understood, may be accomplished by a construction, combination and operative association of parts, such as is disclosed by the drawings which accompany and which form part of this specification.

In the drawings:

Figure 1 is a view looking toward the bottom of a shoe having the improvement applied thereon.

Fig. 2 is a view showing the cork carrying member swung to ground engaging position.

Fig. 3 is a bottom plan view of the improvement, the cork carrying member being in latched position.

Fig. 4 is a sectional view on the line 4—4 of Fig. 3.

Fig. 5 is a sectional view on the line 5—5 of Fig. 3.

Fig. 6 is a sectional view on the line 6—6 of Fig. 3.

The body of my improvement is preferably constructed from a single piece of suitable material, metal preferred, shaped, stamped or otherwise formed to provide a heel plate 1 that has its inner edge formed with an upstanding flange 2, designed to contact with the inner face of the heel 3 of a shoe 4, the plate, of course, resting on the bottom of the heel 3. From the flange 2, the body is extended at a downward arch, as indicated by the numeral 5, the said arched portion designed to be received in the instep portion of the shoe 4, and from the said arch there is a straight extension 6 which is adapted to underlie the sole of the shoe. The main portion of the body, that is the arched portion 5 and the straight extension 6, have a central substantially rectangular opening 8 which is elongated, terminating a comparatively slight distance inward from the outer edge of the portion 8 and a suitable distance outward from the flange 2. This opening materially lightens the body, and also serves an additional purpose which will presently be described. On the under face at the outer corners of the body there are arranged laterally extending longitudinally adjustable clips 9. Each clip comprises an angle member, its lower portion being slotted, as at 10 and being engaged by the head of a binding member 11 that passes through a suitable opening in the said end of the body. Thus the clips may be held adjusted with respect to the body. The angle or vertical end portions of the clips, indicated for distinction by the numeral 12 are slotted, as at 13, and these slots receive therethrough straps 14 which bind the body on the forward or instep portion of the shoe 4.

The heel plate 3 has adjustably connected therewith a second plate 15. The adjusting means, between the plate 15, on which the heel of the shoe rests, and the heel portion 3 of the body may be in the nature of strap

members 16 which are adjustably secured by means 17 to both the plate 15 and the heel portion 3 of the body. The plate 15 has its outer edge rounded and provided with an upstanding flange 18, and to this flange there is secured a guard member 19 which is preferably constructed of leather and which has attached thereto straps 20 that secure the heel portion of the device 10 on the shoe 4.

Preferably, there is arranged on the plate 5, and on the body of the device a compressible facing 21, this facing being especially desirable at the front of the body. 15 The facing serves as a means for absorbing shocks and jars which would otherwise be inflicted on the user of the device.

For distinction, the portions of the body to the opposite sides of the elongated slot 20 or opening 8, therein, are indicated by the numeral 22 respectively. On the under face, at the arched portion 5 of the body, these members 22 are provided with bearings 23 that receive therein a shaft 24. Journaled 25 on the shaft is one end of a plate 25. This plate carries on its under face, and adjacent to its outer end, depending calks 26, the said calks, when in operative position being disposed directly below the outer strip 27 of 30 the body that connects the members 22. Preferably the face of the plate 25 opposite that provided with the calks has arranged on the portion thereof that contacts with the strip 27 a compressible facing 28. The 35 plate 25, at the end thereof provided with the spaced eyes 29 through which the shaft 24 passes is engaged by one leg 30 of a spring. The coiled portion 31 of the spring is arranged around the shaft 24 between the 40 eyes 29, and the second leg 32 of the spring is disposed over and secured to one of the members 22 of the body. The spring is designed to swing the plate to operative position, that is to bring the outer end of the 45 spring under and in contacting engagement with the strip 27 so that the calks are in ground engaging position. However, the plate 25 is normally retained against the body through the medium of a spring influenced pivotally supported latch 33 that is 50 arranged on the outer face of the flange 2. It will be apparent that after the improvement is attached to a shoe the calk carrying plate will be effectively held by the latch 33, so that the said plate is out of 55 ground contacting position. When the latch is released, the spring will influence the plate to swing the same under the body of the improvement and to bring the calks thereof to a position to enter the ground surface. By providing the compressible facings, the user of the improvement will not, 60 as previously stated, be subjected to shocks and jars. The springs which influence the

plate is strong enough to effectively hold the 65 same in operative position. The device is adjustable so that the same may be arranged on varying sizes of shoes and boots and, as previously stated, will not inflict injury to floor surfaces when the plate 25 is held 70 against the body by the latch 33.

Having described the invention, I claim:

1. An anti-slipping device for shoes including a body designed to be arranged on the instep and sole portions of a shoe, and 75 conforming in shape to said portions of the shoe, and a heel portion designed to receive the heel of the shoe, said heel portion comprising adjustable members, means on the heel portion for securing the same to the 80 shoe, means on the outer corners of the body securing the same on the shoe, a spring influenced plate hingedly connected to the arched portion of the body, latching means at the inner end of the said arched portion 85 for holding the plate thereagainst, calks carried by the plate, and said plate designed to swing under the body by its spring influenced means to bring the calks thereon into contacting position when the latching 90 means is released.

2. In an anti-slipping device for shoes, a body member shaped to be received under the shoe and in contact with the instep portion of said shoe, said body having one end 95 flanged downwardly to contact with the inner face of the heel of the shoe and having said flange provided with a heel extension, said extension comprising adjustable members, a guard on the outer edge thereof, 100 means on the guard for securing the same to the heel portion of the shoe, laterally disposed longitudinally adjustable clips at the outer corners of the body, means connected therewith for securing the body on the front portion of the shoe, a spring influenced calk carrying plate hingedly connected to the body, latching means on the flange of the body for engaging said plate for holding the calks against the body, and said plate, 110 when the latching means is released designed to be influenced by its spring means under the body to bring the calks thereof in ground engaging position.

3. In an anti-slipping device for shoes, a 115 body member shaped to be received under the shoe and in contact with the instep portion of said shoe, said body having one end flanged downwardly to contact with the inner face of the heel of the shoe and having 120 said flange provided with a heel extension, said extension comprising adjustable members, a guard on the outer edge thereof, means on the guard for securing the same to the heel portion of the shoe, laterally disposed longitudinally adjustable clips at the 125 outer corners of the body, means connected therewith for securing the body on the front

portion of the shoe, a spring influenced calk carrying plate hingedly connected to the body, latching means on the flange of the body for engaging said plate for holding
5 the calks against the body, and said plate, when the latching means is released designed to be influenced by its spring means under

the body to bring the calks thereof in ground engaging position, and cushioning means on the upper face of the body and between 10 the plate and body.

In testimony whereof I affix my signature.

RAY O. BARDON.
